(57) **CLAIM**

The ornamental design for a flashlight, as shown and described.

DESCRIPTION

FIG. 1 is a top perspective view of the flashlight as seen from the front, top, and left side, lined for the colors black and silver;

FIG. 2 is a top plan view of the flashlight of FIG. 1; and, FIG. 3 is a right side elevational view of the flashlight of FIG. 1, the other side elevational view being a mirror image thereof.

The broken lines showing the remainder of the flashlight are for illustrative purposes only and form no part of the claimed design.
